UNITED STATES PATENT OFFICE.

PIETRO SARACCO, OF TURIN, ITALY.

SPINNING AND TWISTING FRAME.

1,096,059.

Specification of Letters Patent. Patented May 12, 1914.

Application filed January 18, 1913. Serial No. 742,968.

To all whom it may concern:

Be it known that I, PIETRO SARACCO, a subject of the King of Italy, residing in Turin, in Italy, have invented certain new 5 and useful Improvements in Spinning and Twisting Frames, of which the following is a specification.

This invention relates to a spinning and twisting frame in which the spools on which 10 the thread is wound, are given a double movement of rotation about their spindles and of gyration or revolution about an intermediate axis, so as to effect at the same 15 time the twisting of each thread as well as the twisting of the different threads together. To that end, the spools are mounted 20 on a rotating support and are forced to roll during the revolution of their spindles, on a rim which in its turn is rotating, so that by regulating the two rotations, any desired twist can be obtained.

In the accompanying drawing, Figure 1 shows in vertical section a construction of an apparatus according to this invention, 25 Fig. 2 being a plan and Fig. 3 showing a modified construction.

As will be seen from these figures, the support 1 for the spools is secured to a spindle 2 to which is keyed a pulley 3 or a conical 30 pulley for transmitting the motion. On the spindle 2 is rotatably mounted a box 4 provided with a pulley 5 or with a conical pulley for the transmission. The rods 6 to which are secured in the well known manner 35 the spools of thread, are mounted in socket bearings 7, and have keyed to them disks 8, the rims of which, provided with a lining or packing of rubber, leather or hard material such as fiber, metal, etc., can come 40 into contact with the inner surface of the circular rim 10 of the box 4. The bearings 7 of the spindle 6 are mounted in the supporting plate 1 and pass through radial slots 11 in which they are guided (Fig. 3). The 45 support for these socket bearings can be constituted, as shown by way of example in Fig. 1, by a rod 12, to the bottom end of which is pivoted the end of the bearing. A screw 13 is used for fixing the extreme outward 50 position which the bearing can assume in the slot 11, and in that way it is possible to regulate the pressure of the lining or packing 9 on the rim 10. In any case, it is advantageous that when the plate 1 is stand-

ing still, the bearings may be in such position that the spindles 6 are near the center, and that the packing 9 of the disks 8 is not in contact with the surface of the rim 10. To that end can be arranged springs 14 normally pushing the bearings 7 toward the intermediate spindle (Fig. 3) or having the tendency to give them a position inclined toward the center of the apparatus. It is also possible more simply to use an eccentric method of mounting the bearing as shown in Fig. 1, so that its weight has the tendency to incline it toward the axis of rotation of the pivot 2. In any case, when the support 1 is stationary, the spindles 6 with their spools are also stationary for owing to the position of the bearings 7, the rims 9 are not in contact with the rim 10 of the box 4. When however the pivot 2 is rotating, centrifugal force brings the bearings 7 into the position in which the packing 9 of the disks 8 adheres to the surface of the rim 10 and rolls on it, producing at the same time rotation of the spools about their spindles, while the spindles 6 rotate about the central spindle of the support 1. By adjusting the speed of rotation of the support 1 and of the box 4 which generally speaking must rotate in the same direction, any desired proportion will be obtained between the twisting of each individual thread and the twisting of the complete yarn.

The described method of mounting the bearings for the spindles of the spools, so that the rims 9 of their disks are brought into contact with the rim 10 merely by the action of centrifugal force, has the advantage of enabling the spools to be automatically stopped by stopping the rotation of the pivot 2, so that only one gear has to be operated, while it is possible, owing to the rotation of the box 4, to regulate at will the twist given to the thread.

What I claim as my invention and desire to secure by Letters Patent is:—

1. In a spinning and twisting machine, 100 the combination with a rotating support having radial slots, of bearings adapted to move in said slots, means whereby said bearings move away from the outer walls of the slots when the support is standing still, 105 spindles mounted to rotate in said bearings, friction disks on said spindles, an outer rim adapted to be engaged by the friction disks

when the support is rotating, and means for rotating the rim independently of the support.

2. In a spinning and twisting machine, the combination with a rotating support having radial slots, of step bearings extending downward through said slots and supported pivotally and eccentrically at their lower ends, spindles mounted to rotate in said bearings, friction disks on said spindles, an outer rim adapted to be engaged by the friction disks when the support is rotating, and means for rotating the rim independently of the support.
3. In a spinning and twisting frame, a rim, means for driving the rim, a spindle co-axial with the rim, and means for driving the spindle, a member in the interior of the rim and connected to the spindle, means on the member adapted to bear spindles on which the spools are secured, friction disks on the spindles adapted to run on the inner wall of the rim when the central spindle is in rotation, and means where-

by the friction disks move out of contact with the inner wall of the rim when the apparatus is at rest.

4. In a spinning and twisting frame, an outer box having a rim, means for driving the box, a spindle co-axial with the box and means for driving the spindle, a member mounted in the interior of the rim and connected to the spindle, means on the member adapted to bear spindles on which the spools are secured, friction disks on the spindles adapted to run on the inner wall of the box-rim when the central spindle is in rotation, and means whereby the friction disks move away from the inner wall of the rim when the apparatus is at rest.

In testimony whereof I have signed my name to this specification in the presence of two subscribing witnesses.

PIETRO SARACCO.
